PROJECTION LAMP HOLDER

Robert E. Ulrich, Riverton, and Vesper A. Schlenker, Camden, N. J., assignors to Radio Corporation of America, a corporation of Delaware

Application November 29, 1949, Serial No. 130,013

6 Claims. (Cl. 240—52)

1

The present invention relates to projection lamp holders, and more particularly to a miniature, prefocused, projection lamp holder particularly useful in sensory aid instruments for the blind.

Many instruments of a type particularly useful to blind persons for providing information as to the presence of objects in their path depend for their operation upon a projected beam of light which originates from an accurately located light source. Because of the high degree of sensitivity of these instruments, the light source should be provided with a support or holder which will secure it against movement from its position in the instrument regardless of any movements of the instrument or vibrations transmitted thereto during the carrying of the instrument. Projection lamps for these indicating instruments are generally quite small, and in many cases are of the order of approximately one half of an inch in length and one eighth of an inch in diameter. Because of this small size, considerable difficulty is encountered in assembling such a lamp in an instrument and rigidly securing it against further movement. Conventional, prefocused lamps and their holders in use today have not been found satisfactory, particularly for blind aid instruments, either because the lamp is not firmly secured in position to project a beam of light without deviation from a definite axis, or because readjustments of the position of the lamp are necessary with each replacement of the bulb. In addition thereto, the prior art lamp holders known to us have not been of such design that a blind person, who must rely only on his sense of touch, can replace the bulb easily and accurately.

It is, therefore, the primary object of our present invention to provide a projection lamp holder whereby the lamp filament will be accurately located and secured in a fixed position at all times to project a beam of light uniformly along a predetermined axis.

It is another object of our present invention to provide a projection lamp holder for a sensory aid instrument for the blind which permits quick and easy removal of the lamp from its holder and accurate replacement thereof without further focusing adjustments being necessary.

It is still another object of our present invention to provide a projection lamp holder for a sensory aid instrument for a blind person which will enable him to quickly and accurately replace the lamp in the instrument being guided only by his sense of touch.

It is also an object of our present invention to

2

provide a projection lamp holder which is simple and easy to construct and which requires no special skill to effect accurate location of the lamp within an instrument in the event replacement thereof is necessary.

In accordance with our present invention, we provide a projection lamp holder comprising a tubular retaining member which is open at both ends, and a cylindrical housing closely fitting around and providing a light shield for an electric projection lamp, the housing being removably carried within the tubular retaining member. Both the retaining member and the lamp housing are provided with at least one aperture in their respective sides for the emission of light therethrough with the lamp housing aperture being disposed opposite to the lamp filament. The lamp housing, which is dimensioned to be slidably mounted within the retaining member, is provided with a pin extending through the housing for cooperation with a locking slot in the retaining member, the pin and slot also serving as orienting means for aligning the apertures. One portion of the pin member is arranged to receive a tool to facilitate removal and replacement of the lamp and its housing from the retaining member. The housing is of greater length than the lamp and the retaining member is substantially as long as, or longer than, the housing so that the lamp and its housing are secured against movement in the retainer throughout a major portion of the length thereof. A supporting member, which is suitably mounted in the instrument, is provided for the retaining member and is adjustable in different directions in two planes disposed normal to each other to permit accurate positioning of the lamp filament.

The novel features characteristic of our invention, as well as additional objects and advantages thereof, will be better understood from the following detailed description when read in connection with the accompanying drawing in which,

Figure 1 is a perspective view of a projection lamp holder in accordance with our present invention, together with an adjustable support therefore and shown in association with a lens and contact member,

Figure 2 is an enlarged, side view of the electric lamp and housing therefor, a portion of the extraction tool being shown broken away, and

Figure 3 is a central, longitudinal section of the projection lamp holder shown in Figure 1 with the extraction tool being shown in elevation.

Referring more particularly to the drawing,

wherein similar reference characters designate corresponding parts throughout, there is shown a projection lamp holder 1 comprising an elongated, hollow cylindrical retainer 3 which is open at both ends, and an electric lamp assembly 5 comprising an electric lamp or bulb 7 mounted in a housing 9 comprising a hollow, cylindrical, opaque shield or sleeve member which is received telescopically in the retainer 3.

The electric lamp assembly 5 has an outer diameter of slightly smaller dimension than the inner diameter of the retainer 3 so as to be freely slidable therein. The end 11 of the retainer 3 is outwardly flanged to facilitate inserting the lamp assembly 5 within the retainer 3 and functions as a guide therefor. A pin 13 extends laterally through the housing or shield member 9 adjacent an open end 15 thereof and has an end portion 17 extending outwardly from the shield member 9. The retainer 3 is provided with a locking, J-shaped slot 19 starting at the flanged end 11 and extending longitudinally inwardly from the peripheral edge thereof. The slot 19 is dimensioned to slidably receive the pin 13 and lock the lamp assembly 5 securely in the retainer 3 when the pin 13 is disposed in the innermost position at the end 21 of the slot, as shown particularly in Figure 1 of the drawing. The shield member 9 is of greater length than the bulb 7, and the retainer 3 is of a length at least as great as, and preferably of greater length than, the shield member 9 so that, when the shield member 9 is disposed within the retainer 3 and the pin 13 is in the locked position in the slot 19, the retainer will support the shield member 9 throughout the greatest portion of its length.

Another portion 23 of the pin 13 extends diametrically across the interior of the shield member 9 and is dimensioned to receive a tool 25 which has a bifurcated end 27 and may be inserted through the shield member open end 15. The bifurcated end 27 of the tool member 25 is biased to frictionally hold the pin portion 23 between the end portions thereof so that, when the lamp assembly 5 is inserted into the retainer 3, it can be locked readily in the slot 19. After the lamp assembly has been locked in position in the retainer 3, the tool member 25 may be removed easily by pulling it longitudinally outwardly from the shield member 9, a handle 29 being provided in the opposite end of the tool member to facilitate application of the tool member to the pin 13 or mounting the lamp assembly 5 in the retainer 3.

The electric lamp or bulb 7 is provided with a filament 31 and a pair of wire leads 33, 35 connected to the filament and extending outwardly from one end of the bulb 7. The bulb 7 is mounted inside the shield member 9 with the sides of the bulb in closely spaced relation to the internal wall of the shield member 9 and at a predetermined distance from the pin 13. The bulb is securely held in place in the shield member 9, as by cement 37 shown in Figure 3 of the drawing, so that the filament 31 will be disposed at all times in an accurate, prefocused position when mounted in an instrument.

A pair of diametrically disposed apertures 39 is provided in the side of the shield member 9 opposite the filament 31 and in registry therewith for the purpose of passing light through the shield member 9, and another aperture 41 is provided in the retainer 3 for the same purpose. The apertures 39, 41 are so disposed in the sides of their respective members 9, 3 that,

when the lamp assembly 5 is mounted within the retainer 3, the apertures 39, 41 are in alignment and the electric bulb 7 will cast a beam of light along an axis such as that represented by the broken line 43 in Figure 1 of the drawing. The lamp axis 43 may be so arranged that when the lamp and its holder are mounted in an instrument (not shown) fixedly supporting a lens 44 such as the lens pictured in the drawing, the lamp will project a beam of light (not shown) through the lens 44. While two apertures 39 are shown provided in the shield member 9, only one of these apertures is necessary to project the beam of light through the lens 44. The other aperture has been found advantageous in assembling the bulb 7 in the shield member 9 and effecting the proper prefocusing of the lamp filament 31 and orientation thereof with respect to the pin 13 during manufacture of the assembly.

A source of energy (not shown) for making electrical connections to the filament lead wires 33, 35 may be provided in any suitable manner. However, as shown in the drawing, the retainer 3 and shield member 9 are made from metal in order to serve as one of the contact elements for the bulb filament 31 with one of the lead wires 33 being attached to the shield member 9. The other contact element comprises a button 45 mounted in the end 47 of the shield member 9 opposite the end containing the pin 13 and the other lead wire 35 is connected thereto. The button 45 is secured in place by a suitable insulating material 49 and is arranged to engage a resilient contact member 51 mounted on a wall 53 of the instrument housing in which the holder is mounted. The button 45, attached to one end of filament wire 35, and a contact element, including the shield member 9, and the retainer 3, attached to filament wire 33, Figures 1 and 2, perform the function of lighting the lamp by completing the electrical connection between the source of energy (not shown) and the lamp filament 31.

A suitable support or holder 55 is provided for the retainer 3, the retainer being secured to the holder by force fitting or in any other suitable manner. The support 55 is adjustably supported from a walled structure within the instrument with which the lamp holder 1 is associated and is adjustable in different directions in two planes normal to each other, and another plane passing through the lens axis 43. For this purpose, adjusting screws 57 or other suitable adjusting means are provided which are threaded through the walled structure.

Thus, it will become obvious to those persons skilled in the art, that we have provided a projection lamp holder 1 which is particularly adapted for use in instruments for blind people. The holder 1 is not only simple in construction but permits an unskilled person to replace a lamp in the instrument without further adjustments being necessary after the lamp is locked in its retainer in the instrument. Furthermore, the arrangement of interlocking of parts makes it impossible for anyone to incorrectly replace a bulb.

While we have described and illustrated but a single embodiment of our present invention, it will also be recognized that various changes and modifications are possible within the spirit of our invention. Therefore, we desire that the particular form of our invention described herein shall be considered as illustrative and not as limiting.

What is claimed is:

1. In a projection lamp holder, the combination of a retainer having a cylindrical inner surface and an aperture in a side thereof for the transmission of light, an electric bulb having a filament therein, and a housing for said bulb, said housing being slidably mounted within said retainer and having an opening in a side thereof for the transmission of light, said bulb being mounted within and held by said housing with said filament disposed opposite to and in registry with said housing opening, cooperative means on said retainer and said housing for locking said housing and said bulb in fixed position within said retainer, said means being oriented with respect to both said openings in a manner to align said openings one with the other, and said housing being so disposed within said retainer that said retainer supports said housing throughout at least a major portion of its length.

2. An electric lamp assembly adapted for slideable mounting in a hollow, cylindrical retainer having an aperture and also having locking means therein, said lamp assembly comprising a sealed bulb having a filament mounted therein and a pair of leads connected to said filament extending outwardly from said bulb, an elongated opaque, sleeve encompassing said bulb and being at least coextensive with said bulb and constituting a light shield therefor, said sleeve having at least one aperture disposed in a side thereof adjacent to said filament for providing a light channel therethrough, electrical contact means disposed in one end of said sleeve and connected to one of said leads, and means disposed adjacent to the opposite end of said sleeve for cooperation with said locking means for locking said lamp assembly in the retainer.

3. A projection lamp holder comprising an elongated, hollow, cylindrical retainer having at least one end open, a hollow cylindrical shield member telescopically mounted in said cylindrical retainer, said shield member having an open end and an electric lamp having a filament, said lamp being mounted within and held by said shield member, said cylindrical retainer and said shield member each having at least one aperture in their respective cylindrical surfaces, said shield member aperture being disposed adjacent to and in registry with said filament, and said cylindrical retainer in said shield member being provided with interengageable means for effecting and maintaining said apertures in alignment, said interengageable means comprising a pin disposed adjacent to one end of said shield member and having an end portion extending outwardly therefrom, said pin having another portion thereof extending diametrically across the hollow interior of said shield member, the portion of said pin disposed within said shield member being positioned to receive a tool member inserted through said shield member open end to facilitate replacement of said shield member and said electric lamp within said cylindrical retainer, and a locking slot disposed in one end of said cylindrical retainer extending longitudinally inwardly from said one end and dimensioned to slidably receive said first named pin end portion.

4. A projecting lamp holder comprising an elongated, hollow, cylindrical retainer having at least one end open, a hollow cylindrical shield member telescopically mounted in said cylindrical retainer, and an electric lamp having a filament, said lamp being mounted within and

held by said shield member, said cylindrical retainer and said shield member each having at least one aperture in their respective cylindrical surfaces, said cylindrical retainer and said shield member comprise electrical conducting members, said shield member being provided with an electrically conductive contact button mounted in one end thereof and insulated from said shield member, and said lamp being provided with a pair of leads connected to said filament and extending to the exterior of said lamp, one of said leads being connected to said shield member and the other of said leads being connected to said contact button, said shield member aperture being disposed adjacent to and in registry with said filament, and said cylindrical retainer and said shield member being provided with interengageable means for effecting and maintaining said apertures in alignment.

5. A projection lamp holder comprising an elongated, hollow, cylindrical retainer having at least one end open, a hollow cylindrical shield member telescopically mounted in said cylindrical retainer, said projecting lamp holder being provided with support means engaging said cylindrical retainer, and wherein said support means is provided with adjustable means for adjusting said support means and said lamp holder in separate planes normal to each other, and an electric lamp having a filament, said lamp being mounted within and held by said shield member, said cylindrical retainer and said shield member each having at least one aperture in their respective cylindrical surfaces, said shield member aperture being disposed adjacent to and in registry with said filament, and said cylindrical retainer and said shield member being provided with interengageable means for effecting and maintaining said apertures in alignment.

6. An electric lamp assembly adapted for slideable mounting in a hollow, cylindrical retainer having locking means therein, said lamp assembly comprising a sealed bulb having a filament mounted therein and a pair of leads connected to said filament extending outwardly from said bulb, an elongated opaque, sleeve encompassing said bulb and being at least coextensive with said bulb and constituting a light shield therefor, said sleeve having at least one aperture disposed in a side thereof adjacent to said filament for providing a light channel therethrough, electrical contact means disposed in one end of said sleeve and connected to one of said leads, and means comprising a pin extending laterally through said sleeve, a portion of said pin within the interior of said sleeve being positioned to receive a tool inserted through said opposite end of said sleeve to facilitate replacement of said lamp assembly in the retainer.
